(57) **CLAIM**

The ornamental design for a sash astragal extrusion, as shown and described.

DESCRIPTION

FIG. 1 is an isometric front view of a sash astragal extrusion, according to the present disclosure.

FIG. 2 is a top view of the sash astragal extrusion of FIG. 1.

FIG. 3 is a bottom view of the sash astragal extrusion of FIG. 1.

FIG. 4 is a front view of the sash astragal extrusion of FIG. 1.

FIG. 5 is a rear view of the sash astragal extrusion of FIG. 1.

FIG. 6 is a left side view of the sash astragal extrusion of FIG. 1; and,

FIG. 7 is a right side view of the sash astragal extrusion of FIG. 1.

The sash astragal extrusion is shown with two parallel dash-dot break lines that represent the bounds of the claim. The appearance of any portion of the sash astragal extrusion between the break lines forms no part of the claimed design.
